(57) **CLAIM**

The ornamental design of a modular guide link for conveyor chain, as shown and described.

DESCRIPTION

FIG. 1 is a perspective view of the modular guide link for conveyor chain of the present invention;

FIG. 2 is a right side elevational view thereof;

FIG. 3 is a front elevational view, the rear being a mirror image thereof;

FIG. 4 is a left side elevational view thereof;

FIG. 5 is a top plan view thereof; and,

FIG. 6 is a bottom plan view thereof.

The broken lines in the figures are for illustrative purposes only and form no part of the claimed design.
